COUPLER

Frank S. Barks, St. Louis, and Alexander P. Fox,
University City, Mo., assignors to Lincoln Engineering Company, St. Louis, Mo., a corporation of Missouri

Application April 5, 1939, Serial No. 266,146

1 Claim. (Cl. 285—169)

The present invention relates to certain new and useful improvements in couplers for grease-guns, and it relates more particularly to multi-jawed hydraulic chuck type couplers of the general type disclosed in Patent No. 2,040,177. The coupler of the present invention is adapted particularly for coupling onto or for quick detachable connection with round-headed lubricant-receiving fittings or so-called "nipples" of the kind shown in Figure 2 of Patent No. 2,010,174 having a generally hemispherical outer contact surface beneath which an annular groove is formed into which the jaws of the coupler are adapted to engage for interlocking mechanical connection with the "fitting."

One of the objects of the present invention is to provide a multi-jawed hydraulic chuck type coupler which may be more readily assembled and whose parts may be more readily replaced, and which will be more durable and serviceable in actual use.

With the above and other objects in view, the present invention consists of certain novel features of construction, including a generally cylindrical housing, in which the hydraulic piston is adapted to travel, and to which the lubricant conducting hose may be directly connected, and a camming cap member or nose piece threadedly secured to said cylindrical body or housing and projecting beyond said housing just sufficiently to present the camming surface or inclined wedging surface to the gripping jaw; the latter being carried in the main cylindrical body or housing portion, at least to a sufficient extent to permit assembly therein before the application of the cap or nose piece.

The present invention further consists of other novel details and features of construction, all of which will appear more fully from the following detailed description and accompanying drawings.

For the purpose of illustrating the invention, there is shown in the accompanying drawings forms thereof which are at present preferred, since the same have been found in practice to give satisfactory and reliable results, although it is to be understood that the various instrumentalities of which the invention consists can be variously arranged and organized and that the invention is not limited to the precise arrangement and organization of the instrumentalities as herein shown and described.

In the accompanying drawings, in which like reference characters indicate like parts,

Figure 1 represents a longitudinal cross sec-

tional view of a multi-jawed hydraulic chuck type coupler embodying the present invention.

Figure 2 represents a similar cross sectional view of another embodiment of the present invention.

Figure 3 represents a similar cross sectional view of still another embodiment of the present invention.

Figure 4 represents a similar cross sectional view of still a further embodiment of the present invention.

Figure 5 represents a similar cross sectional view showing another embodiment of the present invention.

Figure 6 represents a similar cross sectional view of still another embodiment of the present invention, partly broken away.

Figure 7 represents another cross-sectional view of a still further and modified embodiment of the present invention, partly broken away.

Figure 8 represents a typical elevational view of any of the couplers of Figures 1 to 7, with the cap-like nose piece or front housing portion removed.

Figure 9 represents a cross-sectional view (with the rear end broken away) of another form of coupler construction.

According to the present invention, the main body portion or housing 10 of the coupler is a generally tubular formation having a cylindrical bore 11 therein, of a length sufficient to house not only the piston assembly designated generally by the numeral 12, but also to house the inner ends of the jaws 13.

The interior of the housing may be narrowed or reduced in internal diameter as at 14 and 15, to form a valve seat 16, against which a ball or other similar check valve 17 is adapted to rest. Beyond the restricted portions, the housing is screw-threaded as at 18, either internally as shown in Figure 1 or externally, to receive the screw-threaded terminal fitting of a hose or other conduit through which the lubricant or grease is to be conveyed from the pump or so-called "grease-gun" to the coupler.

The piston assembly designated generally by the numeral 12 may be composed of a central annular composition member 19, formed of an oil-resistant composition such as synthetic rubber, or of leather, cow hide or the like, with sufficient resiliency, so that when compressed axially between the two metallic washers 20 and 21, it will tend to increase its outer diameter and to decrease its inner diameter so that it will fit snugly and in fluid-tight relation to the inner bore 11 of hous-

ing 10 and against the outer cylindrical surface of the tubular sealing plunger 22 which passes through the annular sealing member 19. The annular member 19 is maintained in sliding relation to the cylindrical bore 11 of the housing 10 and also in sliding relation to the outer diameter of the tubular sealing plunger 22.

The tubular sealing plunger 22 is a metallic member, preferably slightly enlarged at its rear end as at 23, so that it may not pass the washer 21. The sealing plunger 22 is preferably formed of steel, and provided at its outer end with a concavely spherical sealing surface 24 of a radius corresponding to the radius of the spherical head portion of the lubricant-receiving fitting with which it is intended to be used (see Figure 2 of Patent No. 2,010,174). Thus, the concave spherical sealing surface 24 is adapted to form a ball-and-socket type contact with the end of the spherically headed lubricant-receiving fitting, so that the coupler may be "angled" with respect to the lubricant-receiving fitting or "nipple" within suitable limits. Thus, when the coupler is tilted at an angle to the fitting, the concavely spherical sealing surface 24 of the sealing plunger 22 will continue to make a sealing contact with the spherical-ended fitting or "nipple."

Three or more jaw members 13 are provided surrounding the sealing plunger 22, and with their inner ends projecting into the cylindrical bore 11 of the main housing or body 10. The outer ends 30 of the jaws 13 are turned inwardly or formed inwardly into claw-like gripping members which are adapted to project into the annular groove beneath the "head" of the fitting or "nipple" (see Figure 2 of Patent No. 2,010,174) or which may engage beneath the head of any "headed" lubricant-receiving fitting or "nipple." The outer claws 25 of the jaws 13 form a generally continuous circle, separated only by short gaps 26, of an extent just sufficient for ordinary manufacturing clearances or tolerances. The jaws 13 and their outer claw portions 25 are of generally equal circumferential extent. In the embodiments here shown, three jaws are used and this number has been found preferable, although more than three can also be used.

The gripping surface or surfaces 27 of the claws 25 are preferably slightly inclined, so that the grip of the coupler on the fitting can be broken entirely by angling the coupler to a sufficient degree so that one of the jaws will release its grip on the shoulder formed beneath the head of the "fitting."

The jaws are also provided with an outer inclined surface 28, by means of which they are given their inward radial motion by a similarly inclined camming surface 29 on the interior of the cap or nose piece 30, which is screw threadedly secured to the end of the housing 10 as at 31.

A compression spring 32 serves constantly to urge the piston assembly 12 as well as the jaws 13 into a forward position or in a forward direction, while a spring 33 is interposed between the sealing plunger 22 and the ball check valve 17, to seat the check valve and also to urge the sealing plunger 22 in a forward direction.

To apply the coupler to the fitting or "nipple," it is merely necessary to push the coupler onto the fitting in a generally longitudinal direction 70 indicated by the arrow 34, either in a true axial alignment with the fitting or at an angle thereto within suitable limits. As the coupler is applied to the fitting in the direction of the arrow 34, the jaws 13 are first forced back together with the

5 piston assembly 12, against the force of the spring 32, until the claws 25 of said jaws are opened up to a diameter sufficient to permit the fitting head to pass between the claws. The sealing plunger 22, and more particularly the concave spherical surface 24 thereof, then contacts the convex spherical sealing surface of the fitting and is pushed back slightly against the force of the spring 33 until the claws 25 engage the shoulder beneath the head of the fitting.

A substantial seal may be maintained with angularity as much as fifteen to twenty degrees off axial alignment between coupler and fitting. At a greater angularity, however, the seal is broken and the coupler is thus detached.

In the embodiment of the invention shown in Figure 2, the sealing plunger 22 is screw threaded at its inner end 35, and is provided with an annular nut-like member 36, which serves to confine the sealing member 19. In this embodiment also, the plunger is provided with a shoulder 37 against which the washer 20 is adapted to rest.

In the embodiment shown in Figure 2, but a single spring 41 is employed and a spring 33 and a ball check valve 17 are omitted. In this embodiment, however, an adapter or nozzle 59 is screw threaded into the screw threaded end 18 of the body 10, with its conical tip 38 forming a seal against the edge 39 of the constricted opening 15. The adapter or nozzle 59 is in turn provided with either an external or an internal thread, as for instance that indicated at 40, to which the hose leading from the grease-gun or pump may be screw threadedly connected, or whereby it may be directly connected to a rigid conduit on the pump or grease-gun. The nozzle or adapter 59 is adapted to receive other couplers or nozzles or connector members, as for instance that shown in Figure 8 of Patent No. 1,966,278, or the conical tip 38 (after the coupler has been removed therefrom) may be used directly by pressing it against the inlet holes of fittings having larger inlet holes, that is, having inlet holes sufficiently large to permit the entry of the conical tip 38.

In the embodiment of the invention shown in Figure 2, the spring 41 serves to urge the metallic sealing plunger 22 forwardly. When the jaws 13 are forced inwardly by the head of the fitting to an extent sufficient to take up the clearance 42 between the nut-like member 36 and the sealing member 19, then the spring 41 also acts upon the sealing member 19 and (through it) upon the jaws 13; tending to push them forward.

In the embodiment of the invention shown in Figure 3, a check valve 17 is provided similar to that shown in Figure 1 but with the valve closing spring 43 retained by a spring retainer cage 44 screw-threadedly secured in the housing at 45. A small by-pass or bleeder hole 46 may also be provided in the housing to by-pass around the check valve 17 in any of the embodiments of the invention utilizing a check valve. The diameter of the opening 46 is sufficiently small that the comparatively viscous lubricant will pass through it only very slowly at normal pressures. The purpose of this hole is to permit the lubricant to pass back into the hose or conduit from where it came so as to relieve the pressure in the coupler and permit it to be uncoupled more readily. However, this by-pass may be omitted.

In the embodiment of the invention shown in Figure 4 the sealing plunger designated generally by the numeral 22-a is formed of two parts, namely, the rear portion 47 and forward

or contact portion 48 preferably united by a press fit or otherwise securely fastened to each other, and with a ball check valve 49 seated against the constricted valve seat 50 formed in the rear end of the part 47 and urged by a valve closing spring 51. The rear end of 47 is shown peened without clearance between 19, 20 and 21.

In the embodiment of the invention shown in Figure 5, an adapter 59 similar to that shown in Figure 2 is provided but having a shoulder 53 formed therein, against which the conical terminal 54 of a secondary check valve member 55 may be seated in sealing relation thereto. The member 55 is screw-threaded to the adapter 59 as at 56. The member 55 in turn is provided with a valve seat 57 against which a check valve 58 is adapted to be seated by a valve closing spring 60. The valve 58 is preferably drilled laterally as at 61 to permit the freer passage of lubricant when the valve is open. The member 55 is again screw-threaded as at 62 either internally as indicated or externally to include the delivery holes or conduit leading from the grease-gun or pump.

In the embodiment of the invention shown in Figure 6, a check valve 17 similar to that shown in Figures 1 and 3 is provided with a valve closing spring 43 held by a cage 63 similar to the cage 44 in Figure 3, but flanged as at 64 for receiving one end of the main spring 41 whereby the cage may be held in place.

In the embodiment of the invention shown in Figure 7, a check valve 17 is inserted from the rear of the housing. In this embodiment the constricted opening 64 in the housing is screw-threaded at its rear-most portion 65, and to this screw-threaded portion an apertured screw plug 66 is threadedly secured. The plug 66 has a central opening 67 which opens outwardly into a valve seat 68 against which the check valve 17 is held by the valve closing spring 69. The plug 66 may be notched across the screw thread thereof as at 70 to a slight extent sufficient to permit a slight by-pass of lubricant around the check valve 17.

The sealing plunger 22 is preferably reduced at its outer diameter as at 71 from its outer end to a point slightly short of the rear ends of the jaw members 13. This permits greater freedom of radial movement of the jaws 13 at their outer ends and yet provides a lateral support for the rear ends of the jaw members 13.

The cap member or nose pieces 30 in the several embodiments of the invention may be so fitted to the forward ends of the housings 10 that the two screw-threaded portions are brought to a limiting position by the shoulders 72 and 73, or they may be so fitted that their limiting positions will be determined by the shoulders 74 and 75 as indicated particularly in Figure 1.

It will be noted that by the coupler construction hereinabove described, no fluid seal or gasket is necessary in uniting the body portions of the housing because the fluid under pressure is confined entirely to the integral body or housing member 10 as the entire travel of the piston assembly 12 takes place within the single and uninterrupted bore 11 of the main body or housing member 10, to the rear end of which the lubricant-delivery hose or conduit is directly connected without the intervention of any sealing gaskets.

By the coupler construction hereinabove described also, the rear ends of the jaw members 13 extend into the generally tubular body or

housing member 10, in such a way that if the nose piece 30 which is attached to and becomes a continuation of the body or housing 10 is removed, the jaw members 13 will be held in place 5 at their bases so that these jaw members may be replaced and re-assembled more conveniently and without resort to any special assembling operations or assembling tools. In coupler constructions heretofore in use, the division between 10 the front part of the coupler body which carries the jaw-operating cam or wedging surface 29 and the rear part of the coupler body to which the lubricant delivery hose or conduit was connected, was made at a point rearwardly of the 15 piston, which would correspond to the piston assembly 12 in the construction hereinabove shown, so that the piston was operatively disposed within the same member which carried the jaw actuating cam or wedging surface at the front end of the coupler. This necessitated the provision of a good fluid-tight seal between the front and rear body parts of the coupler, and also required the assembly of the coupler in such a way that the jaws were inserted first into the front part 20 of the body and the piston assembly and other related parts inserted thereafter. This is an awkward assembly operation, particularly for replacements in the field because of the difficulty of holding the three jaws in place against the jaw-actuating wedging surface in the front part 30 of the coupler body while the sealing plunger and piston and spring are assembled in place behind the jaws.

By the coupler construction of the present invention, this awkward assembly operation is entirely eliminated because the jaws can be put in place after all the other operating parts of the coupler have been assembled. Moreover, they can be put in place without any need for aligning them in relation to the jaw-actuating wedging surface in the nose piece, because the nose piece can be merely superimposed upon the jaw members after the jaw members have been inserted into the main body portion 10 of the coupler. Thus, the nipple-gripping jaws can be removed and replaced by merely unscrewing the cap or nose piece without in any way disturbing the other internal parts of the coupler such as the piston assembly, the nipple-sealing member or plunger, the springs or check valve.

In the forms of construction shown in Figure 1, the nipple-gripping jaws are spring-actuated independently of the nipple-sealing plunger during the initial clamping operation.

While the different constructional features are shown in different figures of the drawings, it is to be understood that the various constructional features illustrated in the several figures of the drawings may all be interchanged and combined in one coupler. Thus, for instance, the adapter or nozzle construction shown in Figure 2 may be applied to couplers of the forms shown in Figures 1, 3, 4, 6 and 7, while the form of spring support plunger construction shown in Figures 2, 3, 5, 6 and 7 may be interchanged. Likewise, any of the by-pass or bleeder constructions shown in Figures 3 and 7 may be applied to the forms of construction shown in the other figures of the drawings.

The springs 32, 33 and 41 are preferably proportioned so that if the cap-like nose piece or front housing member 30 is removed and the springs permitted to expand fully, they will not move the jaws much beyond the position shown in Figures 1 to 7, so that the basal portions of the jaws will still remain in the rear housing por-

tion 10 in the manner indicated in Figure 8. In this condition the jaws 13 may be removed and replaced without disturbing the internal mechanism of the coupler. When the jaws have thus been replaced, the cap-like nose piece or front housing member 30 is merely screwed back in place the coupler is again ready for use.

In Figure 9 another coupler construction is shown to illustrate one phase of the present invention applicable to conventional hydraulic couplers; namely, the phase of the present invention represented by the two-spring and cage construction, one embodiment of which is shown in Figure 6. In this form of construction, the juncture between the rear and front portions of the main body or housing of the coupler is behind the piston 12, so that the entire piston assembly 12 as well as the jaw members 13 are held assembled within the front part of the housing. In this modification, the juncture between the two parts of the housing is through the similarly threaded portions 15 and 16 and a suitable gasket 17 interposed for making fluid-tight seal. The gasket 17 is preferably a soft copper gasket. In this form of construction, the flange 64 of the cage 63 is preferably somewhat larger in diameter and is held in place by the end 18 of the front housing member which is here designated by the numeral 19 (while the rear housing member is designated by the numeral 80). In this form of construction, the valve 17 is closed independently by the spring 43, while the sealing plunger 22 is independently urged forwardly by the spring 41 in the same manner as in the construction shown in Figure 6.

In Figures 6, 7 and 8, the rear part of the housing is broken away. This broken away portion may, however, be of any one of the forms of construction illustrated in Figures 1 to 5 inclusive and in Figure 8.

The present invention may be embodied in other specific forms without departing from the spirit or essential attributes thereof, and it is therefore desired that the present embodiments be considered in all respects as illustrative and

not restrictive, reference being had to the appended claim rather than to the foregoing description to indicate the scope of the invention.

Having thus described the invention, what is hereby claimed as new and desired to be secured by Letters Patent, is:

A multi-jawed hydraulic chuck type lubricant-delivery coupler for use on lubricant-receiving "nipples," including a generally tubular main housing member, and a piston and a nipple-sealing member slidably mounted in said main housing member, a spring urging said piston and nipple-sealing member towards the discharge end of the coupler, a plurality of nipple-gripping jaws surrounding said nipple-sealing member, with a substantial part thereof extending into the aforesaid main housing member and disposed between said main housing member and said nipple-sealing member, said nipple-gripping jaws having outer in-turned claws extending beyond said main housing member, and a generally tubular cap-like nose-piece superimposed upon the projecting outer in-turned claws of said nipple-gripping jaws, said cap-like nose-piece being screw-threadedly secured to said main housing member to form a rigid though detachable continuation thereof, said cap-like nose-piece having an in-turned outer camming flange for cammingly engaging the in-turned outer claw portions of said nipple-gripping jaws; whereby said nipple-gripping jaws may be held in assembled relation to each other and to said main housing member and to said piston and nipple-sealing member, while said cap-like nose-piece is removed from said main housing member, and whereby said nipple-gripping jaws may be removed from and inserted into their assembled positions in the coupler through the front end of said main housing member while said cap-like nose-piece is removed, without the need for disturbing the assembled disposition of said piston and nipple-sealing member and spring in relation to said main housing member and in relation to each other.

FRANK S. BARKS.
ALEXANDER P. FOX.
